MULTIPLE SWIVEL CLAMP FOR TUBES

John Ward Blakely, 4031 Mary Ellen,
Studio City, Calif. 91604

Original design application Aug. 23, 1965, Ser. No. 86,678,
now Patent No. 206,288, dated Nov. 22, 1966. Di-
vided and this application May 9, 1966, Ser. No. 3,901

Term of patent 14 years

(Cl. D54—1)

FIGURE 1 is a perspective view of a multiple swivel clamp for tubes showing my new design;

FIGURE 2 is an end elevational view and a mirror image of the other end;

FIGURE 3 is a side elevational view, the other side constituting an inverted mirror image of FIGURE 3; and

FIGURE 4 is a partial sectional view on the line 4—4 of FIGURE 1.

This is a division of design application Ser. No. 86,678, filed Aug. 23, 1965, now Patent No. D.206,288.

I claim:

The ornamental design for a multiple swivel clamp for tubes, substantially as shown and described.
